MOTOR DRIVEN COMPRESSOR

Filed Dec. 21, 1938

UNITED STATES PATENT OFFICE

2,221,857

MOTOR DRIVEN COMPRESSOR

Jess M. Bartholomew, Michigan City, Ind., assignor to Sullivan Machinery Company, a corporation of Massachusetts

Application December 21, 1938, Serial No. 246,964

8 Claims. (Cl. 230—18)

This invention relates to motor driven compressors, and more particularly to improved controlling mechanism for such compressors adapted to regulate the control thereof by loading and re-loading, or by stop and start, as the demand for air makes preferable, and all in accordance with receiver pressure variations.

Some compressors are subjected to widely varying demands for air, and the nature of the demand may be such that for a considerable portion of the day the compressor is called upon to furnish a rather high percentage of its potential quantity of compressed air. During other portions of the day for substantial periods there may be a much reduced demand for air. During the first type of period it is advantageous to operate on the load and unload system, because the quantity of current required in starting the motor and the wear and tear on the starting switch mechanism can be saved. It has been found that if re-loading follows unloading at comparatively short intervals, a definite saving is possible by operating on the load and unload system as compared with the stop and start system. Where, however, the compressor may run loaded for a few minutes and then be shut down for a quarter of an hour, or perhaps longer, a saving will be possible by stopping the motor when the maximum desired pressure is reached and starting it again when the minimum desired pressure is reached, and this is particularly so where it is possible to have a wide range of pressures between the maximum and minimum. Desirably, when working on the load and unload system, a comparatively narrower range of pressures will be selected for the purpose of avoiding unnecessary motor stoppage.

It is an object of my invention to provide an improved electrically-driven compressor system. It is another object of my invention to provide an improved mechanism for automatically controlling the operation of a compressor. A further object of my invention is to provide an improved controlling mechanism for automatically controlling the operation of a compressor in accordance with the receiver pressure variations, regulating the mode of compressor control in accordance with the nature of the air demand. Still another object of my invention is to provide a controlling mechanism for automatically stopping and starting a motor-driven compressor or for automatically unloading and loading the compressor, dependent upon the nature of the air demand. Yet a further object of my invention is to provide an improved controlling mechanism for controlling the running of a compressor

driving motor and for automatically loading the compressor a predetermined time after the motor has started and for unloading the compressor when the maximum desired receiver pressure has been reached. Still another object of my invention is to provide an improved controlling mechanism for automatically stopping a compressor driving motor a predetermined time after the desired maximum pressure has been reached, and if during such predetermined time the air demand is high, for avoiding the stopping of the motor and resuming a loaded compressor operation. These and other objects will herein-after more fully appear.

In the accompanying drawing there is shown for purposes of illustration one form which the invention may assume in practice.

In the drawing—

Fig. 1 is a diagrammatic view showing a compressor having an electric driving motor and showing the wiring diagram of the mechanism for controlling said motor and loading and unloading of the compressor.

Fig. 2 is an enlarged detail view, partially in vertical central section, through an electromagnetically controlled pilot device.

Fig. 3 is a cross sectional view taken on the line 3—3 of Fig. 2, showing details of the pilot device.

In Fig. 1 there is shown a compressor C of the so-called angle-compound type having a low pressure cylinder 1 and a high pressure cylinder 2 and mounted on a base 3. An electric driving motor 4 is provided for the compressor and is herein shown as a polyphase motor directly connected to the compressor crank shaft 5. Fluid compressed by the low pressure cylinder flows through an intercooler 6 to the high pressure cylinder 2 and, after compression in the latter, is discharged from the compressor through a conduit 7 leading to a receiver 8.

An intake-closure type unloading valve 9 is arranged in the inlet 10 of the low pressure cylinder, and is actuated through a stem 11 connected to a piston 12 of a servomotor 13. When fluid is admitted to the motor 13 to force down the piston 12 and so move the valve 9 to closed position, the admission of air or other fluid to the low pressure cylinder 1 is completely cut off, and the compressor is thereby unloaded. Fluid for actuating the piston 12 is delivered thereto through a pipe 14 under the control of a magnet valve generally designated 15, the magnet valve being connected to the receiver tank 8 by a pipe 16. The pipe 16 is connected to a lower chamber 17 in the magnet valve, and the magnet valve also

5

10

15

25

35

40

45

50

55

has an upper chamber 18, which is connected to atmosphere by a vent port 19. The upper and lower chambers open into a central chamber 20 through aligned passages numbered 21 and 22 respectively. The pipe 14 opens into this central chamber. Valves 23 and 24 seating towards the central chamber control the flow of fluid through passages 21 and 22, and are continuously urged toward closed position by springs 25 and 26. A lever arm 27 is pivoted at one end 28 within the central chamber 20 and is suitably connected at its other end to a plunger 29 projecting within a solenoid 30. The stem portions of the valves 23 and 24 engage upper and lower portions of the lever respectively. When the solenoid 30 is energized the lever arm 27 is swung upwardly about its pivot 28, and the valve 23 is lifted to open the passage 21 between the central chamber 20 and the upper chamber 18. The servomotor 13 is then vented through pipe 14, central chamber 20, passage 21, upper chamber 18 and vent 19. When the servomotor is vented the piston 12 is moved to its upper position by any suitable means, herein represented by a spring 12a, thus opening the valve 9 and loading the compressor. When the solenoid 30 is deenergized, the weight of the plunger 29 moves the lever arm 27 to its lower position, opening the valve 24 and allowing the spring 25 to close the valve 23. The pipe 14 is then connected to the receiver tank 8 through pipe 16, chamber 17, passage 22, and chamber 20, and pressure fluid is conducted to the servomotor 13 to act upon the piston 12 and close the valve 9, thereby unloading the compressor. Suitable high pressure cylinder venting means, herein generally designated H, and of any suitable type, such for example as is shown in the W. E. Hughes Patent No. 1,786,114, granted Dec. 23, 1930, is controlled also by the magnet valve 15, having pressure supplied thereto and vented therefrom through a passage 14a connected with the passage 14.

My improved controlling mechanism is designed, among other purposes, to energize the solenoid 30 after the motor 4 has been started and brought up to speed, to deenergize the solenoid 30 when a predetermined maximum pressure in the receiver tank has been reached, and to reenergize it while the motor 4 continues to operate if the demand for air is above a predetermined rate. My improved mechanism is furthermore designed to start and stop the motor in accordance with receiver pressure variations and to determine whether the motor shall be stopped or the compressor reloaded instead, depending upon the demand for pressure fluid.

I have herein, as a part of my improved controlling system, provided a pair of pressure switches 31 and 32. The pressure switch 31 is designed to close when receiver pressure drops to, say 80 pounds, and to be opened when any desired higher pressure below the desired maximum pressure, which we will assume to be 100 pounds, is reached. It may be assumed to open, for the purpose of illustration, at 85 pounds. Pressure switch 32 closes when receiver pressure falls, say, to 98 pounds and opens when receiver pressure rises to 100 pounds, in the illustrative embodiment of the invention disclosed herein.

The motor 4 is adapted to have its leads 36, 37 and 38 connected by a main line contactor switch 39 to the power lines 33, 24, 35. A solenoid 40 is provided for closing the main line contactor switch 39, and is adapted to do this when energized. A time relay 41 controls the solenoid

circuit and operates to close the same a predetermined time after the coil 42 of the relay 41 is energized. Current to energize the coil 42 is supplied by a control circuit including a manually operated switch 43, which is closable to establish 5 a connection with the main line wire 35, a conductor 44, the switch element 31' of the pressure switch 31, a conductor 45, time relay coil 42, and conductors 46 and 47, the latter connected to the main line wire 34. If the pressure acting on 10 the pressure switch 31 be below 85 pounds and the manually operated switch 43 be closed, current will flow through the circuit described to energize the time relay coil 42; and after a predetermined time the relay 41 will complete, 15 through the solenoid 40, a circuit which includes the manually operated switch 43, the conductor 44, the pressure switch element 31', a conductor 48, a conductor 49, the switch element 32' of the pressure switch 32, a conductor 50, time relay 41, 20 a conductor 51, solenoid 40, and a conductor 52 leading to main line wire 34. The main line contactor switch 39 will then be closed by the energized solenoid 40 and the motor 4 will be started. A circuit through the solenoid 30 of the 25 magnet valve 15 is controlled by a time relay 53 which may be of any standard type and is adjusted to operate after the main line contactor switch 39 has been closed and the motor 4 has been brought up to full speed. As will shortly 30 appear, the coils of the relays 41 and 53 are energized at the same time. However, time relay 53 is of the type which opens immediately when deenergized, but closes only after the desired time delay when energized, while relay 41 is of the 35 type which closes immediately when energized, but does not open until after a predetermined delay. With the receiver tank pressure below 85 pounds and the manually operated switch 43 closed, a circuit through the coil 54 of the time 40 relay 53 exists which includes the manually operated switch 43, connected to line wire 35, the conductor 44, pressure switch element 31', conductors 45 and 48, conductor 49, pressure switch element 32', a conductor 55, time relay coil 54, a 45 conductor 56 and the conductor 47 leading to the main line wire 34. After the elapse of the time period required for the closing of the time relay 53, a circuit is established through the manually operated switch 43, conductor 44, pressure switch element 31', conductors 45 and 48, conductor 57, the solenoid 30, a conductor 58, the time relay 53, and the conductors 56 and 47 back to the main line wire 34, and the magnet valve 15 is operated to vent the servomotor 13 and 55 load the compressor.

A holding circuit is established when the main line contactor switch 39 closes, to hold the main line switch closed even after the receiver pressure has increased to such a value as to cause the 60 pressure switch 31 to open. This holding circuit includes a switch element 59 which is connected to and operates with the main line switch 39. The switch element 59 is connectible through a conductor 60 and the manually operated switch 43 to 65 the main line wire 35. A contact of the switch 59 is connected through a conductor 61, conductor 55, conductor 50, time relay 41, conductor 51, solenoid 40 and conductor 52 to the line wire 34, thereby forming, on closure of switch element 59, the holding circuit for the main line switch 39. Another holding circuit is set up at the same time to maintain the time relay 41 closed. This circuit extends from the main line wire 35, through the manually operated switch 70 75

43, conductor 60, switch 59, conductors 61, 55, pressure switch element 32', conductor 49, conductor 48, conductor 45, time relay coil 42, conductor 46 and conductor 47 back to the main line wire 34. Still another holding circuit is established through the time relay coil 54 to hold the time relay 53 closed for a time after the pressure switch 31 opens, and this circuit includes the manually operated switch 43, conductor 60, switch element 59, conductor 61, time relay coil 54, and conductors 56 and 47, the latter leading back to the main line wire 34. The solenoid 30 is maintained energized after the pressure switch 31 opens by current flowing from the main line 15 through the manually operated switch 43, conductor 60, switch element 59, conductors 61 and 55, pressure switch element 32', conductors 49 and 57, solenoid 30, conductor 58, time relay 53, conductor 56, and conductor 47 leading to the 20 main line wire 34. A manually operated switch 62, shunting the pressure switch 31, is provided to start the motor 4 when the receiver pressure is above that at which the pressure switch 31 will remain closed.

25 In the operation of my improved control, assuming that the equipment has been shut down and that the receiver pressure is below 85 pounds it will be evident that pressure switches 31 and 32 will both be closed. To initiate operation of the 30 equipment, the operator then manually closes switch 43, whereupon the time relay coil 42 is energized by current flowing between lines 35 and 34 through the switch 43, conductor 44, pressure switch element 31', and conductor 45, coil 42, and conductors 46 and 47. Relay 41 immediately closes the circuit including switch 43, conductor 44, switch element 31', conductors 48 and 49, switch element 32', conductor 50, relay 41, conductor 51, coil 40 and conductor 52, closing the main line switch and starting the motor 4. At the same time that coil 42 is supplied with current, current also flows through the conductors 48 and 49, pressure switch element 32', conductor 55, time relay coil 54 and conductors 56 and 47. The time relay 53, however, being, as above explained, of the delayed closing type, does not close the circuit which it controls until after the motor 4 has had time to be started and bring the compressor up to a safe speed. After the motor 4 has attained a suitable speed, however, the time relay 53 brings about energization of the solenoid 30 through a circuit including the conductors 51 and 58, as previously described, and the solenoid 30 in turn operates the magnet valve 15 to cause loading of the compressor. When the receiver pressure builds up and the pressure switch 31 opens, the motor 4 will continue to drive the compressor loaded and the latter will remain loaded because the switch 59 closed at the same time the main line switch closed and established a circuit through the manually operated switch 43, conductor 60, switch 59, conductors 61, 55, 50, time relay 41, wire 51, solenoid 40 and wire 52, to hold the main line switch closed while time relay 41 remains closed, and concurrently established circuits through the time relay coils 42 and 54 to hold the time relays 41 and 53 closed, thereby, until the switch 32 opens, respectively holding the circuit closed for energizing the solenoid 40 (which in turn, as just explained, holds the line switch 39 closed to operate the motor 4) and holding the circuit for energizing the solenoid 30 energized to keep the compressor loaded. When the receiver pressure reaches the desired maximum, suggested to be, for purposes of illustration, 100 pounds, the pressure 55 switch 32 opens, thereby breaking the circuit through the solenoid 30 which includes the switch 43, conductor 60, switch 59, conductors 61 and 55, pressure switch element 32', conductors 49 and 57, solenoid 30, conductor 58, time relay 53, and conductors 56 and 47, and the compressor is unloaded. At the same time the circuit through the time relay coil 42 is broken, but the time relay 41 remains closed for a predetermined period, as above explained, and the solenoid 40 accordingly 10 continues to be energized, thereby holding the line switch 39 closed to supply current to the motor 4, and the compressor operates unloaded for a selected period. If the demand for air is heavy the receiver pressure may drop sufficiently, 15 e. g., to 98 pounds, to allow the pressure switch 32 to close before the time relay 41 operates to open the line switch holding circuit. When this happens the circuit through the solenoid 30 is again closed to operate the magnet valve 15 and 20 load the compressor, and the circuit through the time relay coil 42 is re-completed to hold the time relay 41 closed and to maintain the solenoid 40 energized. If the demand for air is light, however, and the time relay 41 opens before the receiver pressure drops to 98 pounds, the circuit through the solenoid 40 will be broken, and the line switch 39 and switch 59 will open. The circuit through the time relay coil 54 is also broken then, and the time relay 53 opens. The solenoid 30 25 will now not be energized again automatically to close the line switch 39 until the receiver pressure drops to the lower setting of pressure switch 31, say 80 pounds, at which time the pressure switch 31 will close to establish circuits again 35 through the time relay coils 42 and 54 and bring about motor starting and compressor loading.

If it is desired to start the compressor before the receiver pressure drops to 80 pounds, the hand switch 62 may be held closed until the motor 4 is started; then the switch 62 may be opened again and, due to the holding circuits described, the motor 4 will continue to drive the compressor loaded until the receiver pressure reaches 100 pounds again. 40

It will of course be understood that the various pressure limits herein described may be varied in accordance with desired operating conditions, and that the pressure at which the pressure switch 31 is opened may be widely varied between 50 that at which it closes and the pressure at which switch 32 opens.

45 From the foregoing description, it will be clearly apparent that I have provided an improved controlling mechanism for starting a 55 compressor when the receiver pressure falls to the minimum limit, and for continuing the compressor in operation on the unload and re-load system as long as the demand for air is high. It will be further evident that the improved automatic controlling mechanism is operative without operator intervention to change the system of compressor control to stop and start operation when the air demand becomes less. When the air demand again increases, the structure described will again automatically return to the load and unload system of regulation. It will be evident that the controlling system is simple and has no parts which should be likely to be a source of trouble in operation. 60

70 While there is described and illustrated in this application one form which the invention may assume in practice, it will be understood that this form of the same is shown for purposes of illustration and that the invention may be modified. 75

fled and embodied in various other forms without departing from the scope of the appended claims.

What I claim as new and desire to secure by Letters Patent is:

- 5 1. In a compressor system, in combination, a compressor, unloading means therefor, a driving motor for said compressor, a control switch for said driving motor, and compressor discharge pressure responsive devices for controlling the operation of said control switch and said unloading means, one of said pressure responsive devices operative to close at one compressor discharge pressure and to open at a higher discharge pressure, and another of said pressure responsive devices operative to close at a discharge pressure above that at which said first mentioned pressure responsive device opens and to open at a still higher discharge pressure.
- 10 2. In a compressor system, in combination, a compressor, unloading means therefor, a driving motor for said compressor, a control switch for said driving motor, compressor discharge pressure responsive devices for controlling the operation of said control switch and said unloading means, one of said pressure responsive devices operative to effect closure of said control switch and start said motor, and means operative with said control switch for making the second pressure responsive device effective to maintain said control switch closed after said first pressure responsive device opens.
- 15 3. In a compressor system, in combination, a compressor, unloading means therefor, a driving motor for said compressor, a control switch for said driving motor, compressor discharge pressure responsive devices for controlling the operation of said control switch and said unloading means, means operative immediately after operation of one of said pressure responsive devices for effecting closure of said control switch and starting said motor, and a switch operative with said control switch for completing a circuit through a second pressure responsive device and said second mentioned means to maintain said control switch closed after said first pressure responsive device opens.
- 20 4. In a compressor system, in combination, a compressor, unloading means therefor, a driving motor for said compressor, a control switch for said driving motor, compressor discharge pressure responsive devices for controlling the operation of said control switch and said unloading means, means operative on operation of one of said pressure responsive devices for effecting closure of said control switch and starting said motor, means operative a predetermined time after closure of the control switch for effecting loading operation of said unloading means, and a switch operative with said control switch for completing separate circuits through the second pressure responsive device and through said second and third mentioned means for maintaining said control switch closed and said compressor loaded after said first pressure responsive device opens.
- 25 5. In combination, a compressor, an electric driving motor therefor, an electrically operated starting switch for said motor, unloading means for said compressor having electrical control means operative on energization to effect compressor loading, a time delay relay for controlling said starting switch and operative on current supply thereto to effect immediate current

supply to effect closure of said switch and upon interruption of current supply thereto to interrupt operating current supply to said switch only after a predetermined time delay, a time delay relay for controlling the control means for said unloading means operative only after a predetermined delay following current supply thereto to supply current to effect loading and operative immediately upon interruption of current supply thereto to discontinue current supply to said control means and effect unloading, and controlling means for said time delay relays including pressure responsive devices operative at predetermined limits of receiver pressure to control circuits supplying current to said time delay relays. 15

6. Apparatus for controlling a prime mover operated compressor comprising a compressor discharge pressure responsive device arranged to control the loading and unloading of said compressor and the running and stopping of the prime mover, said pressure responsive device including a switch operable at an upper limit to effect unloading of said compressor and stopping of said prime mover after a predetermined time or operative at a lower limit to close and reload 25 said compressor and effect continued running of said prime mover if the lower limit is reached before the end of the predetermined time, means operative if said prime mover stops due to opening of said switch to preclude restarting thereof by closure of said switch, and means operative only on a further predetermined drop in pressure to effect restarting.

7. Apparatus for controlling a prime mover operated compressor comprising, in combination, 35 unloading means for said compressor having electrical control means operative on energization to effect compressor loading and on deenergization compressor unloading, time delay means having electrical control means operative on energization to effect operation of said compressor and a predetermined time after deenergization a stopping of the compressor, pressure responsive means arranged to simultaneously deenergize the electrical control means for said unloading means and said time delay means when the compressor discharge pressure reaches a predetermined value 40 and to reenergize said electrical control means if the compressor discharge pressure drops to a predetermined lower value before said compressor is stopped, and means including a pressure responsive device operative at a predetermined pressure below the lower operating pressure of said pressure responsive means for reenergizing the electrical control means of said time delay 45 means if said compressor is stopped.

8. In a compressor system, in combination, a compressor, unloading means therefor, a driving motor for said compressor, a control switch for said driving motor, and compressor discharge pressure responsive devices for controlling the operation of said control switch and said unloading means, one of said pressure responsive devices operative to close at one compressor discharge pressure and to open at a higher discharge pressure, another of said pressure responsive devices operative to close at a discharge pressure above that at which said first mentioned pressure responsive device closes and to open at a discharge pressure higher than that at which 70 said first mentioned pressure responsive device opens.

JESS M. BARTHOLOMEW.
